UNITED STATES PATENT OFFICE.

FRANK H. SYMONS, OF BOSTON, MASSACHUSETTS, ASSIGNOR TO HENRY G. JORDAN, OF SAME PLACE.

COAL-SCREEN.

SPECIFICATION forming part of Letters Patent No. 557,172, dated March 31, 1896.

Application filed October 9, 1895. Serial No. 565,125. (No model.)

To all whom it may concern:

Be it known that I, FRANK H. SYMONS, of Boston, county of Suffolk, State of Massachusetts, have invented an Improvement in 5
5 Coal-Screens, of which the following description, in connection with the accompanying drawings, is a specification, like letters on the drawings representing like parts.

This invention has for its object to improve 10
10 the construction of coal-screens, whereby wet coal may be thoroughly screened and the sieve constantly prevented from becoming clogged.

In accordance with this invention the sieve is suitably supported in inclined position and 15
15 means are provided for moving it bodily back and forth or sidewise quite rapidly, thereby shaking it as the coal passes down, and reciprocating strikers are provided which rapidly strike or tap the bottom of the sieve, thereby 20
20 vibrating it while it is being shaken. The means employed for actuating the strikers is such that they strike a sudden blow, and by their action the sieve is prevented from clogging. The means employed for shaking the 25
25 sieve consists of a crank motion, and the strikers are operated to tap the bottom of the sieve when the crank or cranks are substantially upon their dead-centers, at which time the sieve is practically at rest, and this is im- 30
30 portant in that it prevents undue wear which would otherwise occur.

Figure 1 shows in perspective a coal-screen embodying this invention; Fig. 2, a cross-section of the machine, taken on the dotted 35
35 line xx ; and Fig. 3, a detail showing the cam and crank in the respective positions which they will occupy just before releasing the hammer.

The screen is composed of the sieve a , side 40
40 pieces a' , supporting rods or bars a^2 located beneath the sieve a , and said screen is loosely suspended by rods a^3 from any suitable frame (not shown) in an inclined position, and the ends of the screen are loosely connected by 45
45 chains a^4 with a suitable frame (not shown) to prevent too much longitudinal movement.

The screen is adapted to be shaken by moving it back and forth or from side to side rapidly, and to accomplish this result I have 50
50 provided a power driving-shaft b , supported in an inclined position in suitable bearings

provided for it, and have secured to said shaft cranks b' , two being herein shown, one at each end of the shaft, and the outer ends of said cranks are connected by links b^3 with the 55
55 screen. As the shaft is revolved the screen will be rapidly moved back and forth. By providing cranks for thus shaking the screen it will be observed that the screen is at rest at each time the cranks are upon their dead- 60
60 centers.

Screens provided with means for thus shaking them back and forth are old; but for screening wet coal they are absolutely useless, because the sieve a soon becomes clogged or 65
65 choked, and to obviate this difficulty I have provided means for vibrating the sieve a , which, as herein shown, consist of strikers adapted to strike the bottom of the sieve or the supporting-rods, two of which are herein 70
70 shown. They are made alike, and each consists of a head c , suitably capped or otherwise protected at the end, which is secured to an arm c' pivoted to the frame, as at c^2 , and the arm c' has a projection c^3 , which is acted upon 75
75 by a cam c^4 , which is designed to depress the arm against the stress of a return-spring c^5 . The cam c^4 is secured to the shaft b and is shaped to depress the striker and then permit it to return instantly by the action of its 80
80 spring c^5 . As the striker returns, its head c strikes the bottom of the sieve a —as, for instance, it may strike one of the supporting rods or bars a^2 —and thereby instantly sets the sieve in vibration. 85
85

As two strikers are provided, I prefer to actuate them alternately, and hence the actuating-cams are disposed upon the shaft b reversely for the accomplishment of this result.

To prevent undue wear incident to the 90
90 heads of the strikers rubbing along the moving sieve, the parts are so arranged or timed that the cams release the strikers when the cranks b' are upon their dead-centers, the sieve at such time being practically at rest, and by 95
95 referring to Fig. 3 such arrangement of parts will be seen. The sieve is hence in constant vibration while it is being shaken back and forth.

I claim—

100
100 In a coal-screen, the combination of a sieve loosely suspended in an inclined position, the

rotating shaft b , crank b' thereon, and link b^2 connecting said crank with said sieve, the pivoted spring-actuated striker c, c' , and cam c^4 secured to said shaft b , constructed and arranged to move said striker in opposition to its actuating-spring and to release it while the crank is upon its dead-center, substantially as described.

In testimony whereof I have signed my name to this specification in the presence of 10 two subscribing witnesses.

FRANK H. SYMONS.
